CIGARETTE CASE

Georg Reitzel, Gelnhausen, Germany, assignor to Drescher & Kiefer, Gelnhausen, Germany, a firm, and Randolph-Rand Corporation, New York, N.Y., a corporation of New York, jointly

Filed Aug. 11, 1964, Ser. No. 81,245

Term of patent 14 years

(Cl. D85—2)

FIG. 2

FIG. 1

FIG. 3

FIG. 4

FIG. 5

FIG. 1 is a front elevational view of a cigarette case showing my new design;

FIG. 2 is a side elevational view of the lefthand side of the cigarette case;

FIG. 3 is a side elevational view of the righthand side of the cigarette case;

FIG. 4 is a rear elevational view, and

FIG. 5 is a top plan view of the cigarette case.

The characteristic feature of my design resides in a cigarette case, the lid of which has the particular configuration and appearance shown herein.

I claim:

The ornamental design for a cigarette case, as shown and described.
